UNITED STATES PATENT OFFICE.

PHINEAS L. BARTHOLOMEW, OF AURORA, ILLINOIS.

PAPER-BAG-MANUFACTURING MACHINE.

No. 918,815.

Specification of Letters Patent. Patented April 20, 1909.

Application filed March 18, 1907. Serial No. 362,997.

To all whom it may concern:

Be it known that I, PHINEAS L. BARTHOLOMEW, a citizen of the United States, residing in Aurora, county of Kane, and State 5 of Illinois, have invented a new and useful Improvement in Paper-Bag-Manufacturing Machines, of which the following is a specification.

The object of my invention is to improve, 10 generally, in a paper bag manufacturing machine adapted to cut and fold the base of the bag into the diamond fold, the cut producing shafts and cylinders; the feed; the spreaders and ironers; and particularly the 15 gripping and folding cylinders.

My main object is to provide means for 20 completely severing the bag tube in bag lengths before delivering the said bag portions to the folding and gripping cylinders. My invention consists of certain details of 25 construction, hereinafter set forth, pointed out in my claims and illustrated in the accompanying drawings in which,—

Figure 1 is a view in side elevation of my 30 machine, some of the parts being broken away. Fig. 2 is a view in elevation of the opposite side of the same, some of the parts being broken away. Fig. 3 is a detail sectional view of the mechanism employed for 35 raising the shaft 83, said view being taken on the section line 3—3 of Fig. 5. Fig. 4 is a longitudinal sectional view, taken on the line 4—4 of Fig. 5. Fig. 5 is a plan view of the machine. Fig. 6 is a sectional view, 40 taken on the horizontal line 6—6 of Fig. 1, showing in plan view the parts of the machine below the horizontal path of the blanks. Fig. 7 is a view in elevation of the 45 parts at the delivery end of the machine. Fig. 8 is a perspective view of the gripping and folding cylinders together with a partially formed bag. Fig. 9 is a view in longitudinal section of the tongue plate, taken on the line 9—9 of Figs. 10 and 11. Fig. 10 is 50 a plan view of a portion of the tongue plate or former. Fig. 11 is a view of the same from beneath. Fig. 12 is a view in longitudinal section of the folding and gripping cylinders and associated parts. Fig. 13 is 55 a transverse section of the two feeding and gripping cylinders, taken on line 13—13 of Fig. 12. Fig. 14 is a detail section taken on line 14—14 of Fig. 12. Fig. 15 is a sectional view, taken longitudinally through one of 60 the feeding and gripping cylinders, on line 15—15 of Fig. 13. Fig. 16 is a cross-section

of the machine, taken on line 16—16 of Fig. 4. Fig. 17 is a cross-section of the machine, taken on line 17—17 of Fig. 4. Fig. 18 is a face view of the feeding and gripping cylinders and the spreaders, illustrating the action of the latter on the partially formed bag.

Referring to the accompanying drawings, 65 10 and 11 indicate the longitudinal side frame-members of the machine, said side frame-members being connected and rigidly secured to each other by means of cross bars. The said longitudinal frame-members 10 and 11 are alike and on the same are 70 mounted all of the operative parts of the machine.

Mounted on a support near the rear end of the machine and extending longitudinally forward therefrom through the central portion of the machine is a horizontal tongue plate 12, said tongue plate extending forward into operative relation to the gripping and folding means, for purposes herein-after set forth. When reference is herein 80 made to the rear and forward ends of the machine the receiving and delivery ends respectively are intended to be designated and when reference is had to certain portions of the machine being located on the 85 upper part and certain portions being located on the lower part, the tongue plate 12 is used as the dividing line. Beneath the rear portion of the said tongue plate 12 is secured a lower plate 14, the two plates 12 90 and 14 being joined by a narrower longitudinal plate 13 in the usual manner. Said plates 12 and 14 are separated somewhat at their rear extremities and converge toward one another at their forward ends. The 95 lower plate 14 extends to a point about midway between the rear and the forward ends of the tongue plate 12, and the longitudinal grooves formed between the side margins of the upper and lower plates are 100 designed to receive the bellows folds of the paper tube as the same is formed and fed into the machine; the rear ends of said plates 12 and 14 forming parts of appliances for forming a bellows-folded tube 105 from a continuous roll of paper.

15 and 16 indicate laterally arranged horizontal folders which extend into the grooves between the side margins of the plates 12 and 14 and act to complete the formation 110 of the bellows folds by pressing them into said grooves.

17 and 18 indicate guide plates which also form parts of the tube-forming device. Said guide plates extend transversely from the rails 10 and 11 to points beneath the 5 plate 14. The guide plate 18 is at the rear of the guide plate 17.

19, 19 indicates two presser roller which are located beneath the plate 14 forward of the guide plate 17 and which are adapted to 10 act on the overlapping margins of the web of paper beneath said plate 14, so as to press the same upwardly into contact with said plate. The rollers 19, 19 are yieldingly supported by means of horizontal, longitudinally arranged arms 190, 190 (Fig. 4) which are pivoted on standards 191, 191 on the machine frame, and on the forward ends of which the said rollers are mounted. The 15 said forward ends of the arms 190, 190 are thrown upwardly and the rollers 19, 19 are pressed toward the plate 14 by means of springs 192, 192, shown as having the form of expansively acting coiled springs, which surround upright rods 193, 193 that are 20 pivoted at their upper ends to the rear ends of the arms 190, 190 and pass through guide apertures in fixed brackets 194, 194 on the machine frame; the said springs bearing at their upper ends on said brackets and at 25 their lower ends on nuts applied to the lower ends of the said rods. The rollers 19, 19 are inclined with respect to the central, longitudinal line of the machine in such manner that their forward edges are nearer 30 together than their rear edges; the inclined position of said rollers, in the construction illustrated, being secured by the arrangement of the supporting arms 190, 190 there-of in rearwardly divergent relation, as seen 35 in Fig. 6. The arrangement of the said rollers in inclined position, as described, has the effect that the rollers, as the bellows-folded tube is drawn forward over the plates 12 and 14, act on the overlapping edges of 40 the web, with which they are in contact, in a manner to draw said edges together or toward each other, and to thereby counteract any tendency in said edges to become 45 drawn apart or separated from each other 50 as the tube is advanced. As the bellows shaped paper tube advances over the plates 12 and 14, the bellows folds are moved through the grooves between the margins of the said plates; the lower part of the tube 55 consisting of the marginal parts of the web which are designed to overlap and be joined to each other by means of an adhesive substance, being folded beneath the lower plate 14. One of the lateral margins of the web 60 is threaded between the rearmost guide 18 and the lower plate 14 and the other lateral edge thereof is threaded between the forward guide 17 and the said lower plate. As 65 the said paper tube thus applied to the plates 12 and 14 has already been provided on

one lateral margin with paste or other adhesive substance it is obvious that the two lateral margins of the web, when brought into overlapping relation and drawn between the guide plate 17 and the bottom surface of the plate 14 will be pressed together to complete the pasting of the tube. The presser wheels 19, 19 hereinbefore described operate to carry inwardly the overlapping margins of the tube, thus keeping the freshly 70 pasted parts together. 75

20 and 21 indicate bearing standards mounted on the rails 10 and 11, respectively, and adapted to receive and support journal boxes 22, 22 in which are mounted a transverse, horizontal shaft 23, located below the plane of the tongue plate 12, and provided with fixed collars 24, 24 on which are mounted longitudinally arranged cutting knives 25, 25, each of which is designed to produce at the proper place a longitudinal cut in the lower part of the paper tube. Said knives are shown as having the form of flat plates secured to the inner faces of radial arms formed on said collars 24, 24, 80 85 integrally therewith. 90

In the shaft 23 centrally between the collars 24, 24 is formed a transverse guide passage 26 adapted to receive a transversely arranged knife-bar 27 which is arranged to 95 slide endwise in said guide passage. On one end of said knife-bar 27 is mounted a transverse cutting knife 28. Said bar, when in its normal position, holds the cutting knife inwardly from its operative or cutting position and the said knife-bar is retained in such normal position by means of a coiled spring 29 applied to the end of the knife-bar which projects from the side of the shaft 23 opposite the knife. The knife-bar 27 is 100 actuated by means of an arm 30 mounted rigidly on a transverse, horizontal rock-shaft 31, which said rock-shaft is actuated by a cam 32 on the shaft 23. Said rock-shaft 31 is provided with an upwardly extending rigid arm 195, shown in Figs. 6 and 16, and in dotted lines in Fig. 4. Said arm 195 acts on the edge of the cam 32, which latter has at one point on its periphery an outwardly extending projection 110 adapted to shift said arm 195 outwardly or in a direction to lift the arm 30. A coiled spring 196, applied around the rock-shaft 31, tends to hold the arm 195 in contact with said cam 32. The gearing employed to drive 115 the shaft 23 is so timed, and the rock-shaft 31 carrying the arm 30 is so constructed, and the cam 32 is so timed, as to cause the lever 30 to make an upward stroke, and act on the lower end of the knife-bar 27 to 120 force the latter upwardly at the precise time that the knife-bar 27 is upright and the knife 28 is in position to act on the lower fold of the paper tube. The lower tongue plate 14 is provided with an orifice adapted 125 130

to receive the longitudinal and transverse cutting knives, which act upwardly on the part of the paper tube passing beneath said plate 14, as described.

- 5 33, 33 indicate journal boxes which are mounted in the standards 20 and 21 in vertical alinement with and above the journal boxes 22, 22. Said journal boxes 33, 33 are adapted to receive and support the ends of 10 a transverse, horizontal shaft 34 mounted on the upper portion of the machine or above the plane of the tongue plate 12. Said shaft 34 is provided with collars 197, 197 (Figs. 4, 5 and 16), bearing knives 198, 198 and 15 with a central transverse guide passage 199 provided with a knife-bar 200 on which is mounted a cutting knife 201, and with a spring 202 adapted to retain the said knife-bar in its normal position, and associated 20 with said shaft 34 is a rock-shaft 203, provided with an arm 204 adapted to act on the upper end of said knife-bar, together with a cam 205 secured to said shaft 34 and adapted to act on an arm 206 on said rock-shaft 203, which latter is provided with an 25 actuating spring 207, all of these parts being similar to the parts as described in connection with the shaft 23, with the exception that the cutting knife 201 is, in this instance, of U-shape, as fully shown in the drawings. The upper tongue plate 12 is provided with recesses to receive the cutting knives on the shaft 34.

- 35 and 36 indicate standards mounted on 35 the rails 10 and 11, respectively, slightly forward of the standards 20 and 21, said standards 35 and 36 being designed to support journal boxes 37 and 38 in which is mounted a transverse, horizontal shaft 39 provided 40 on its central portion with a cylinder 40. Said shaft and cylinder are located below the plane of the tongue plate 12, and the cylinder is provided in its central portion with an annular depression or wide and 45 shallow groove 41 (Figs. 4, 6 and 17). The lower tongue plate 14 terminates at a point immediately in the rear of the cylinder 40 and the upper tongue plate 12 is provided with deep lateral notches 42 and 43 (Fig. 50 10) making the part of the tongue plate adjacent to the roller 40 slightly less in width than is the annular depression 41 in said roller. The under surface of said narrow portion of the tongue plate 12 is 55 adapted to engage the surface of the cylinder 40 in the said depression 41.

- 44 and 45 indicate journal boxes, mounted in the standards 35 and 36, in vertical alinement with, and immediately above, the journal boxes 37 and 38. In the said journal boxes 44 and 45 is mounted a transverse shaft 46 located above and parallel with the shaft 39. Mounted on said shaft 46 is a cylinder 47 of the same size as the cylinder 65 40 and located immediately above the same

and constituting a companion cylinder thereto. In the central portion of the cylinder 47 is an annular shallow groove or depression 48 of the same width as the annular depression 41 in the cylinder 40.

49 and 50 indicate annular depressions in the end portion of the cylinder 47 (Fig. 17), each located between the depression 48 and one end of the said cylinder 47. The larger portions of said cylinder 47, at either side of the annular depressions 49 and 50, are in contact with the larger end portions of the cylinder 40. The said cylinders 40 and 47 operate as feed cylinders for moving the paper tube formed in the machine; the same being adapted to grip the side margin of the paper tube at opposite sides of the annular, central depressions 41 and 48 therein. The cylinder 47 is provided with transverse cutting knives 51 and 52 located transversely of the annular depressions 49 and 50, adapted to produce additional cuts in the paper tube as the same passes between the said cylinders. The cylinder 47 is also provided with creasing knives 208 and 209 acting to produce creases in the paper tube as the same passes between the said cylinders. The lower cylinder 40 is provided with recesses 210, 211 to receive the cutting knives 51 and 52 and with like recesses 212, 213 to receive the creases 208, 209, as clearly seen in Fig. 17.

53 and 54 indicate standards located on the rails 10 and 11 a short distance in advance of the standards 35 and 36, and in 100 which are mounted journal boxes 55 and 56. In said journal boxes is mounted a transverse, horizontal shaft 57 provided in its central portion with a cylinder 58. Located centrally in the cylinder 58 is an annular 105 shallow depression 59, and located midway between the said depression 59 and the ends of said cylinder 58 are other shallow depressions 60 and 61. Said depressions 60 and 61 are so located as to be in line with the 110 lateral edges of the paper bag tube. Located within the depressions 60 and 61 are grooves 62 and 63, respectively, designed to receive longitudinally extending guide wires 64 and 65 (Figs. 4 and 6). Said guide wires are, 115 at their rear ends, secured to a cross bar 66 mounted on the rails 10 and 11; said cross bar being located immediately at the rear of the said cylinder 58 and the said guide wires extending forwardly through said grooves 120 between the cylinder 58, and its companion cylinder hereinafter described, to the gripping and folding cylinders, hereinafter described.

Secured to the end portions of the shaft 125 57 are cams 67 and 68 designed for purposes hereinafter set forth, and located on one of the ends of the said shaft 57 outside of the journal box 55 is another cam 69 designed for purposes hereinafter set forth.

Located immediately above the journal boxes 55 and 56, in the standards 53 and 54, respectively, are journal boxes 70 and 71, respectively, in which are mounted the ends of a transverse, horizontal shaft 72 which is located above and parallel with the shaft 57 and on the central part of which is secured a cylinder 73, the same in size as the cylinder 58. The said cylinder 73 is provided near each of its ends with annular depressions 74 and 75 arranged to register with, and to operate as companions to, the annular depressions 60 and 61 in the lower cylinder 58 and located centrally in the cylinder 73 is a shallow annular depression 76 which is considerably wider than the annular depression 59 in the lower cylinder 58. At a point at the rear of the cylinders 73 and 58, the upper tongue plate 12 is broadened to its normal width and extends forwardly between the cylinders 58 and 73 to the gripping and folding cylinders. 77 and 78 indicate two like orifices or openings arranged side by side in the said tongue plate 12; said orifices or openings extending from a point in the rear of the cylinders 58 and 73 to a point in advance of the said cylinders. The annular depressions 60 and 61 of the lower cylinder 58, together with their companion depressions 74 and 75 in the upper cylinders 73, are designed to afford spaces for the passage between the cylinders of the lateral, longitudinal parts of the tongue plate 12, outside of the orifices 77 and 78, and the companion central depressions 59 and 76 in said cylinder afford spaces for the passage between the said cylinders of the central, longitudinal portion of the said tongue plate located between the said orifices 77 and 78. The said cylinders 58 and 73 are designed as companion feed cylinders and the upper cylinder 73 is provided with transverse cutting knives 214, 215 and creasers 216, 217 which coöperate with suitably located recesses in the lower cylinder 58, and are intended to cut and crease the paper tube as it passes between the said cylinders.

The operation of the means employed for severing the bag from the tube, as the same proceeds through my machine, is as follows: By the operation of the knives carried by the shaft 23, a central, transverse cut is made in the lower layer of the tube, by the action of the transverse knife 28, and at the same time by the action of the knives 25, 25, two longitudinal cuts are made exterior to the ends of, and extending rearwardly from, such central transverse cut. By the operation of the knives carried by the shaft 34, a central, U-shaped cut is made in the upper layer of the tube, by the action of the cutter 201, and at the same time, by the action of the cutters 198, 198, two longitudinal cuts are made laterally outside of the U-shaped

cut and extending rearwardly from a line drawn transversely of the tube at the rear ends of the U-shaped cut, as seen in Fig. 5. By the action of the cutters 51 and 52, on the roller 47, two transverse cuts are made extending through both side margins of the paper tube and passing through both of the bellows folds, these cuts being transversely in line with the central, transverse cut made by the knife 28, and also transversely in line with the rearward ends of the U-shaped cut made by the knife 201, as seen in Fig. 5. By the action of the knives 214 and 215 on the cylinder 73, two transverse cuts are made in line transversely with the central transverse cut made by the knife 28, and with the two marginal transverse cuts made by the knives 51 and 52; the said knives 214 and 215 being wide enough to make cuts extending from the inner ends of the marginal cuts to the ends of the said central cut in the lower layer and to the ends of the U-shaped cut in the upper layer; thereby completely severing the tube. The transverse cuts last made by the action of said knives 214 and 215 extend to or meet the forward ends of the longitudinal cuts made by the knives 25, 25 and 198, 198. Such complete severing of the tube does not take place until the forward end thereof has entered between and became engaged by the folding and gripping cylinders, by which the advance end of the severed section of the tube is opened and the diamond fold is made, as hereinafter described.

79 and 80 indicate standards attached to the rails 10 and 11, respectively, forward of the standards 53 and 54. In said standards 53 and 54 are mounted journal boxes 81 and 82 for a horizontal, transverse shaft 83. The said journal boxes are adapted for a limited vertical movement in the said standards, as will be hereinafter explained. Mounted centrally on the shaft 83 is a cylinder 84, said cylinder being hollow and provided within the interior thereof with gripping devices, as will be hereinafter explained. In the surface of the said cylinder near its center are two circumferential grooves 85 and 86 designed to receive guide wires 87 and 88 which are secured to a cross bar 89, said cross bar being located immediately at the rear of the cylinder 84 below the tongue plate 12 and secured to the journal boxes 81 and 82. Secured also to the journal boxes 81 and 82 are forwardly extending brackets 90 and 91, adapted to support journal boxes 92 and 93, which are adapted to slide horizontally in guide slots in said brackets and are pressed rearwardly therein by means of coiled springs 220 and 221. Said journal boxes 92 and 93 support a shaft 94 which extends across the machine parallel with and forward of the cylinder 84, and has mounted on its central portion

a cylinder 95 of the same length as the said cylinder 84 and adapted to act in connection therewith as a feed roller; said cylinder 95 being of much smaller diameter than the 5 said cylinder 84. Attached to the end of the shaft 83 outside of the rail 10 is a gear wheel 93 which meshes with a pinion 97 secured to the adjacent end of the shaft 94. Attached to the opposite end of the shaft 10 83, outside of the rail 11, is a beveled gear wheel 98, designed for purposes hereinafter set forth.

Mounted in the standards 79 and 80, above and in vertical alinement with journal boxes 15 81 and 82, are journal boxes 99 and 100 for a horizontal transverse shaft 101 which is located above and parallel with the shaft 83. Said shaft 101 has on its central portion a cylinder 102 which is adapted to 20 act with the cylinder 84. The said shaft 101 is provided at one end, outside the rail 11, with a rigidly attached gear wheel 103, and immediately outside of the gear wheel 103 the shaft 101 has attached to it a beveled 25 gear wheel 104, designed for purposes hereinafter set forth.

The cylinders 84 and 102 are provided with gripping devices and with cams for actuating the same which are alike for both 30 of the cylinders, and which will now be described in connection with the cylinder 102, it being understood that the description will apply equally to the parts on the cylinder 84, which are correspondingly numbered on the 35 drawings.

The cylinder 102 is hollow and is provided with a longitudinal slot extending the entire length of the cylinder, and in said slot is located a bar 105, equal in length to 40 the cylinder. The bar 105 has mounted upon it parts constituting two gripping devices, one at each end of the cylinder, the gripping jaws of which are located at the side of the cylinder diametrically opposite 45 the said bar. Said gripping devices at both ends of the cylinder are alike, and a description of one will apply to both, the parts of both gripping devices being numbered alike in the drawings. Said bar 105 is grooved 50 longitudinally in its inner surface at some distance inwardly from each of its ends. Secured centrally to the inner face of said bar 105 is a U-shaped bracket 106, having two arms which extend transversely of the 55 cylinder and the ends of which extend through apertures 107 and 108 formed in the wall of the cylinder diametrically opposite the bar 105, and near the ends of the cylinder; the end surfaces of said arms being flush with the surface of the cylinder. Pivoted to the central portion of the U-shaped bracket 106 are two pairs of levers 60 65 109 and 110; the levers of each pair being located on opposite sides of the U-shaped bracket. Said levers extend from their

points of pivotal connection with the center of the bracket 106 toward one end of the cylinder, and parallel with and inside of the bar 105, with their outer ends exterior to the arm of the said bracket at that end of the cylinder. Pivoted to the outer ends of the said levers 109 and 110, by means of a pivot 111, is a transversely extending gripper arm 112, said gripper arm being approximately parallel with the outer face of 70 the adjacent arm of the bracket 106. Said gripper arm 112 is connected with the adjacent bracket arm by means of a pair of connecting links 113 and 114 located one at each side of the bracket and gripper arms. 80 On the free end or extremity of the said gripper arm 112 at right angles thereto is a gripping finger 115, said gripping finger being directed inwardly and extending over the end face of the adjacent bracket arm, 85 the said end of the bracket arm and the gripper finger forming the jaws of a gripping device.

116 indicates a lever arranged parallel with and located in a longitudinal recess in 90 the inner surface of the bar 105. Said lever 116 is pivoted between its ends to the said bar 105. The inner extremity of said lever 116 extends to a point opposite the central portions of the levers 109 and 110, and is 95 pivotally connected therewith by means of a link 117. The outer extremity of said lever 116 extends beyond or outside of the end of the bar 105 and is provided with an anti-friction roller 118 designed to engage a suitably located cam. The pivot of the lever 116 is at a point inside the end wall of the cylinder 102 and on said end wall of said cylinder is a coiled spring 119 which acts on the lever 116 at a point between the pivot of the said lever and the antifriction roller on its outer end. The said spring 119 holds the lever 116 normally in position with its outer end at the outward limit of its swinging movement, and maintains the inner end 105 of the lever 116 at the inward limit of its movement. In this position of the lever 116 the gripper arm 112 will be in position with its gripper finger 115 away from the end of the adjacent bracket arm. Inward pressure upon the antifriction roller 118 will cause the levers 109 and 110 to be drawn outward with the effect of shifting the gripper arm 112 toward the bar 105, the links 113 and 114 acting to draw the swinging 110 end of said gripper arm toward the bracket arm, while the gripper finger on the end of said gripper arm is brought into gripping engagement with the end of the bracket arm. The cylinder 102 is provided with a second 115 longitudinal slot in which is located a bar 124, on which are mounted the parts of a second gripping device. Said bar has attached to its inner surface, at its center, a bracket 125 which extends diametrically 120 125 130

across the cylinder and has its extremity extended through an aperture formed in the wall of the cylinder midway between the ends of the same; the end of the 5 bracket being flush with the surface of the cylinder. The bracket 125 is made of U-shape, having parallel arms which are attached to the bar 124.

127 indicates a longitudinally arranged 10 lever located in the inner surface of the bar 124. Said lever 127 is pivoted to the bar by a pivot pin 128, and its outer end extends outwardly beyond one end of said bar, while its inner end extends to the center of said bar. 15 Said inner end of the lever 127 is pivoted to a slide-bar 129 which has endwise sliding movement between the parallel arms of the bracket 125 (Fig. 15). Attached to the opposite side faces of the bar 129 are two 20 parallel bars 134 and 135 (Fig. 13), the ends of which extend past or overlap the parallel arms of the bracket 125. Between the outer ends of said bars 134 and 135 are pivoted the inner ends of two gripper arms 130 and 131 25 which extend transversely of the cylinder and have their outer ends extended through the slot in the cylinder at opposite edges of the bracket 125. The outer ends of said gripper arms are provided with inwardly extending gripper fingers 132 and 133 adapted to coact with the end surface of the said bracket, over which said fingers extend. 30 136 and 137 indicate pairs of links, which are pivoted to the bracket 125 and severally 35 to the gripper arms 130 and 131. Said links are arranged obliquely in such manner that when the gripper arms are moved bodily inward or toward the bar 124 the outer ends of the gripper arms which stand normally 40 a short distance away from the side edges of the bracket, will be drawn toward the latter. The gripper fingers are carried into gripping contact with the end face of the bracket by an inward shifting movement of 45 the bar 129 and the bars 134 and 135, to which said gripper arms are pivoted. The lever 127 projects outwardly to a point beyond the end of the said bar 124 and is provided on its outer end with an antifriction 50 roller 138. In the end wall of the cylinder 102 is a coiled spring 139 which presses outwardly on the lever 127 at a point between its pivot 128 and the antifriction roller 138. The spring thus arranged holds the outer 55 end of the lever 127 normally at the outward limit of its swinging movement and retains the inner end of said lever 127 and the bar 129 in position to maintain the gripper fingers 132 and 133 raised or away from the 60 adjacent end of the bracket 125. Inward pressure on the antifriction roller 138 will cause the inner extremity of the lever 127 to move outwardly, thus causing the gripper fingers 132 and 133 to approach each other

and to come into gripping engagement with 65 the end face of the bracket 125.

140 (Fig. 12) indicates a segmental cam mounted concentrically with the cylinder 102 in position to act on the left hand antifriction roller 118 in the turning of the cylinder 70 102 for operating the left hand gripper arm 112. Said cam 140 is supported from the journal box 100 by means of a flanged plate 120 which is directly attached to said journal box, and horizontal rods or studs 121, 121 75 which rigidly connect the said cam with the said flanged plate. 141 indicates a like cam which is supported on the journal box 99, and is adapted to engage the antifriction roller 118 for operating the right hand gripper arm 112. Said cam 141 is supported from the box 99 by means of a flanged plate 122 attached to the journal box and horizontal rods or studs 123. 142 indicates a second 80 segmental cam which is secured to the journal box 99 and is adapted to act on the antifriction roller 138 for operating the gripping arms 130 and 131. Said cam 142 is shown as having the form of a cylindric segment which is attached to the inner end of 85 the journal box 99 and extends therefrom inwardly toward the end of the cylinder 102. The lever 127 extends beyond the end of the cylinder 102 a sufficient distance to bring the antifriction roller 138 exterior to the path of 90 rotation of the antifriction roller 118, so that the cam 141 will be free from the roller 138, while the cam 142 will engage the antifriction roller 138 without coming in contact 95 with the antifriction roller 118. 100

The gripper fingers 115, 115 on the gripper arms 112, 112 are so located as to be in line with the side margins of the bellows shaped paper tube, as the same passes between the cylinders 84 and 102, and the gripper fingers 105 132 and 133 are so located as to be in line with the side edges of the U-shaped tongue on the upper fold of the tube, made by the U-shaped knife 201 on the shaft 34. The cylinder 84, as hereinbefore stated, is like the 110 cylinder 102 and is provided with gripper arms and means for actuating the same exactly similar to the parts on the cylinder 102 just described, the outer gripper fingers 115, 115, 132, 133 on said cylinder 84 being in 115 line with the similarly lettered gripper fingers on the cylinder 102, and being similarly adapted to engage a bellows folded paper tube. The journal boxes 81 and 82 are each provided with cams 140, 141 and 142 similar 120 in every respect to the correspondingly numbered cams secured to the journal boxes 99 and 100, as hereinbefore described.

Devices are provided for giving rising and falling movement to the lower cylinder 125 84, which are duplicated for the opposite sides of the machine, and each of which is made as follows: Beneath each of the jour-

nal boxes 81 and 82 and mounted for upward and downward vertical movement, is an upright lifting rod 143, the lower end of which is pivoted to the forward end of a lever 144, 5 arranged horizontally and pivoted between its ends to the rail 10. The rear extremity of the said horizontal lever is provided with an antifriction roller 145 engaged by a cam 67 on the shaft 57 (Fig. 3). The cams 67, 68 10 on the opposite ends of the said shaft 57 are exactly alike and are adapted to press downward on their respective antifriction rollers at the same time, thereby at one time lifting both of the journal boxes 81 and 82 to an 15 equal extent and correspondingly lifting both ends of the shaft 83 and cylinder 84. The upward movement of the said cylinder 84 is sufficient to bring the same into contact with the cylinder 102. The normal position 20 of the cylinder 84 is away from or out of engagement with the cylinder 102.

The shaft 101 of the cylinder 102 is driven through the gear wheel 103 thereon. Means for driving the shaft 83 from said shaft 101 25 is provided, embracing a vertical shaft 147, a beveled gear wheel 146, meshing with the beveled gear wheels 104 on the shaft 101, and a beveled gear wheel 148 meshing with the beveled gear wheel 98 on the shaft 83. The 30 gear wheel 146 is mounted in a bracket 226 on the journal box 100, and the beveled gear wheel 148 is mounted in a bracket 227 attached to the journal box 82. The vertical shaft 147 passes through and is rigidly secured at its upper end in the hub of the gear wheel 146, while the lower end of said shaft passes through and has endwise sliding and splined connection with the gear wheel 148. 35 As the beveled gear wheels 146 and 148 are mounted in the brackets 226 and 227 so that they are held constantly in mesh with the gear wheels 104 and 98, while the wheel 148 is adapted for vertical movement on the shaft 147, it is obvious that the shaft 83 will 40 be continuously driven from the shaft 101 notwithstanding the vertical movement of said shaft 83 and its journal boxes 81 and 82.

The forward extremity of the tongue plate 12 extends to a point between the cylinders 50 84 and 102, and is provided with two notches, forming three prongs, as seen in Figs. 10 and 11. Secured to the under surface of said tongue plate are three flat, spring fingers 149, 150 and 151, all of which have 55 their free extremities directed forwardly and bent or deflected obliquely downward. As hereinbefore described, the paper tube is completely severed when it passes between the cylinders 58 and 73, and as the forward 60 end of the severed tube passes from the forward end of the tongue plate to the folding and gripping cylinders, the upper and lower folds, caused by the bellows shape of the tube, are at said forward end of the severed 65 tube separated somewhat vertically by the

action of the springs 149, 150 and 151, which press downwardly on the lower fold. It will be remembered that the cylinders 84 and 102 are separated, or at some little distance apart, when the shaft 83 is in its normal position and, consequently, space is afforded between the cylinders, at such time, to permit the opening of the folds of the bellows shaped tube as just described. The gripper fingers 115, 115 on the cylinder 102 grasp 70 the lateral edges of the upper bellows folds of the paper tube, at the required time, and at the same time the corresponding gripper fingers on the cylinder 83 operate to grasp 75 the lateral edges of the lower bellows fold 80 of the tube. Prior to this time, and as the bag is entering between the gripping cylinders, the centrally located spring 149, on the end of the tongue, forces the U-shaped tongue, on the lower fold of the tube, downwardly into position to be gripped by the gripper fingers 132 and 133 on the cylinder 84 while the U-shaped tongue on the upper fold of the tube will have been already gripped 85 by the fingers 115 and 121 on the upper cylinder 102. As the severed bag thus gripped continues to advance between the cylinders 84 and 102, the shaft 83 is moved upward until the cylinders 84 and 102 come in contact one with the other, and as the forward 90 surface of the two cylinders are moving away from each other the gripper fingers on the upper cylinder moving upward and those on the lower cylinder moving downward, the upper and lower layers of the 100 tubular bag are drawn away from one another, thus starting the diamond fold.

The creasers 208 and 209 on the rollers 40 and 47, and the like creasers 216 and 217 on the rollers 58 and 73 operate to cross crease 105 the tube, so as to break the stiffness of the paper without injury thereto, and form a defining line to facilitate the laying of the upper fold of the bag back to follow the bottom fold as the bag leaves the gripping cylinders after the formation of the diamond fold.

The gripper fingers 132 and 133 on the lower cylinder 84 retain their engagement with the tongue on the lower fold of the bag until said tongue has been carried downwardly far enough to be caught between the cylinder 84 and the feed cylinder 95, by which the bag is carried downwardly to and between the pasting and folding cylinders 115 hereinafter described. As soon as the bag 120 has become engaged by said feed cylinders 95 the several gripping fingers 115, 115, 132 and 133 are released to free the bag from the gripping cylinders.

152 and 153 are spreaders or spreader arms which operate to open the bellows folds as the end of the bag advances from between the gripper cylinders 84 and 102, and to thereby aid in the formation of the 130

diamond fold, as shown in dotted lines in Fig. 8 and in Fig. 18. Said spreader arms are supported and operated by means as follows: 154 indicates a horizontal cross-bar secured at its ends to the standards 79 and 80 and extending over the cylinder 102. Said cross bar supports two spring-actuated rock-shafts 155, 156 which are mounted in bearings upon the cross-bar, and extend in 10 a direction lengthwise of the machine. The spreaders hereinbefore mentioned are secured to the forward ends of said rock-shaft and depend from the same with their lower ends below the level of the path of 15 the bag. The said rock-shafts are each provided with a rocker-lug which is rigidly attached to its rear end, said lugs being alike and extending inwardly or toward each other, as seen in Fig. 12. Said lugs are 20 acted upon by a rocker arm 157 on a horizontal, transverse rock-shaft 158 which is mounted in bearings rising from the cross bar 154. The outer end of said shaft 158 is provided with a crank arm 228 which extends downwardly from the shaft. Said crank arm is connected by a pitman 159 with the upper end of an upright lever 160 (Fig. 1) which is pivoted at its lower end to the rail 10. On said lever 160 is an anti- 25 friction roller 161 arranged in position to be acted upon by a cam 69 on the shaft 57. The said lever 160 is held in position, with its antifriction roller engaging the cam 69, by means of a coiled spring 162 connecting 30 the said lever to the standard 53. The cam 69 is arranged to operate the spreader arms 152, 153 so as to spread the same apart or throw them outwardly, just before the upper and lower folds of the bag are released, 35 40 from the gripping cylinders.

Devices for pressing the end portions of the bellows folds flat against the top and bottom folds, and to thereby complete the diamond fold are shown as follows: 163 45 indicates a cross-bar secured to the rails 10 and 11 at a point in advance of the cylinders 84 and 102, said cross bar affording a support for two standards 164 and 165 (Fig. 7) in which are mounted transverse, horizontal rock-shafts 166 and 167, arranged in 50 vertical alinement with each other. The upper shaft 166 extends through one of the standards and is connected by means of a rigid crank arm 168 thereon, with the upper 55 end of a pitman 169 through which the said rock-shafts are actuated. Extending from the central portions of the shafts 166 and 167 are rigidly attached arms 170 and 171 which extend from the rock-shafts rearwardly or toward the gripping rollers. The ends of said arms 170 and 171 carry 60 horizontal, transverse rods 172 and 173 on the ends of which are carried upright ironers 174 and 175. Each of said ironers 65 is pivotally connected with the rods 172 and

173, which are at the same distance apart vertically as the shafts 166 and 167, so that, as the shafts 166 and 167 are given rocking movement, the ironers are moved toward and from the gripping cylinders 86 and 102 70 but are always maintained in their vertical position.

The pasting and folding rollers of the machine consist of large upper and lower rollers 230 and 231 mounted on horizontal 75 shafts 232 and 233 which are mounted on the rear end of the machine frame below the feed cylinder 84. A presser roller 234 acts against the rear face of the upper roller 230 in position to grip the advance ends of the 80 bags as the latter pass downwardly between the cylinders 84 and 94. Said presser roller 234 is mounted at its ends in pivoted spring-actuated levers 235 mounted on the rails 10 and 11. The details of construction 85 in and operation of said pasting and folding rollers need not be herein described as they constitute no part of the present invention.

The upright pitman 169 through the medium of which motion is given to the 90 rock-shafts 172 and 173 and the ironers is actuated by means as follows: As clearly seen in Fig. 3, said pitman 169 is pivotally connected at its lower end with the rear end of a horizontal lever 236, the forward 95 end of which is pivoted to the side of the machine frame. Said lever 236 extends below one end of the shaft 233 of the lower roller 231, and on said shaft is secured a cam 237 which is adapted to act on a roller 100 238 mounted on the lever 236 between the ends of the same.

The driving means for actuating or giving rotary motion to the several rotative shafts of the machine, hereinbefore described, is constructed as follows: 240 indicates a horizontal, transversely arranged main driving shaft to which continuous rotary motion is given and which is mounted in suitable bearings below the two side rails 110 10 and 11 of the machine frame. Secured to one end of the said shaft 240 is a gear wheel 241 which intermeshes with an idler 242 mounted on the rail 10. The idler 242 meshes with a gear wheel 243 on the adjacent end of the shaft 39, as clearly seen in Fig. 1. On the opposite end of said shaft 39 outside of the machine frame (Fig. 2) is secured a gear wheel 244. Said gear wheel 244 meshes with a gear wheel 245, of the 115 same diameter, on the shaft 46, so that said shafts 39 and 46 are driven at the same speed. The gear wheel 244 meshes with two idlers 246 and 247, mounted on the rail 11, one at the rear and the other forward of the said gear wheel 244. The idler 246 intermeshes with a gear wheel 248 on the shaft 23, and on said shaft 23 is a second gear wheel 249 which meshes with a gear wheel 259 of the same diameter on the shaft 120 125 130

34. The idler 247 meshes with a gear wheel 250 on the shaft 57, and said gear wheel 250 meshes with a gear wheel 251 of the same diameter on the shaft 72. The gear wheel 250 on the shaft 57 meshes with an idler 252 mounted on the outer face of the rail 11 and said idler 252 meshes with another idler 253, which is mounted on the standard 80 and meshes with the gear wheel 103 on the shaft 101. The shaft 83 is driven from the shaft 101 by the upright shaft 147 and the beveled gearing associated therewith, as hereinbefore described. The idler 252 also meshes with another idler 254 mounted on the machine frame below and to the rear thereof. Said idler 254 meshes with another idler 255 which in turn meshes with the gear wheel 256 on the shaft 233. Said gear wheel meshes with a gear wheel 257 of the same diameter affixed to the adjacent end of the shaft 232.

The operation of the machine in the preliminary cutting of the bellows-folded tube and in the formation of the diamond fold 25 on the pieces or sections severed from the bellows-folded tube to form separate bags, is as follows: The web of paper is fed to the machine in the usual manner and is formed into a bellows-folded tube by the action of the tongue plates 12 and 14, the folders 15 and 16 and the guide plates 17 and 18. As the tube is fed forward its upper fold or layer is provided with a U-shaped cut, by the action of the knife 201, and two longitudinal cuts, by the action of the knives 198, 198, while its lower fold or layer is provided with a transverse cut by the action of the knife 28 and with two longitudinal cuts by the action of the knives 25, 25. Thereafter, the marginal parts of both bellows folds are partially severed by two transverse cuts made by the knives 51 and 52, as hereinbefore described. After the forward end of the tube is reached and became engaged 40 by the cylinders 84 and 102, a section or length to form a bag is completely severed from the tube by the cutters 215 and 216 on the cylinder 73. The leading end of the tube, as the same approaches the cylinders 50 84 and 102, is opened or spread apart by the action of the springs 149, 150 and 151 on the advance end of the tongue plate 12. As the forward end of the tube advances beyond the cylinders 58 and 73, the same rests 55 upon and is guided by the rods 64 and 65, which extend from the grooves in the cylinder 58 horizontally forward to points adjacent to the cylinder 84. The top fold of the bag section, as the tube is fed forward, 60 passes at its side margin beneath the jaws or grippers 132, 133 of the upper cylinder, which grippers catch the side edges of the tongue on the advance end of the upper layer of the bag section, the cam 142 being 65 arranged to act on the roller 138 at the

proper time to operate the grippers at the time the tongue on the top layer enters beneath the same. The tongue on the lower layer of the bag section at the same time enters beneath and is gripped at its side 70 margins by the grippers 132, 133 of the lower cylinder, and the side edges of the lower bellows folds enter beneath and are gripped by the grippers 115, 115 on said lower cylinder. By the further turning of the cylinders 75 84 and 102, after the tongues on the upper and lower layers have been so gripped by the gripping fingers 115, 115, 132, 133, the advance ends of the upper and lower layers are spread apart or carried upwardly 80 and downwardly. Shortly after the ends of the upper and lower folds of the bag section have been carried past the central vertical line of the opposing cylinders, the side margins of the upper and lower bellows folds 85 enter beneath the jaws 115, 115 of the side clamps on both of the cylinders, which jaws are closed, by the action of the cams 140, 141 on the rollers 118, 118, to catch and hold the said side margins of the upper and 90 lower bellows folds at the ends of the creased line for the cross fold, made by the creasers, as hereinbefore described. The continuous rotation of the upper and lower cylinders 84 and 102 carries the bag section forward 95 with the grippers and side clamps holding the same until the grippers 115, 115 of both cylinders have reached a vertical plane passing through the forward periphery of the cylinders, at which time the edges of the 100 bellows folds will have been drawn in into a vertical position to form the diamond fold. After the diamond fold is so formed, the grippers 132, 133 and 115, 115 on both cylinders will be released by the passing of the 105 rollers 118, 118 and 138 from contact with the cams 140, 141 and 142. The spreaders 152 and 153 are opened out just before the grippers are released, and the free ends of these spreaders strike against the inbend of 110 the bellows fold and thereby break or open out the fold so as to form the straight, oblique folding lines for the bottom of the bag. The grippers of the lower cylinders retain their hold upon the tongue of the 115 lower layer of the bag section until such tongue has been carried into engagement with and gripped by the feed roller 94 which acts with the cylinder 84 to draw or carry the folded end of the bag downwardly 120 and deliver it between the cylinder 230 and the feed roller 234. In its passage downwardly from the cylinder 86 to the said cylinder 230 and feed roller 234, the advance end of the bag section is guided by the rods 125 87 and 88, which are carried downwardly in front on the cylinder 86, as seen in Fig. 4. At the time of the release of the grippers the ironers 175 and 176 are thrown forward 130 toward the cylinders 86 and 102 pressing

the inwardly turned side flaps inwardly against the faces of the top and bottom folds or layers of the bag section. Said ironers are not intended to press with any force 5 against the bottom of the bag, but act merely to prevent the side flaps from bulging outward as the bottom of the bag is carried down. After the folded bottom passes the feed roller 94 it is carried to the folding 10 and pasting rollers by which the end flaps of the bottom are turned inwardly and the pasting of said end flaps together is accomplished.

The lower cylinder 86 is given rising and 15 falling movement in order that the upper and lower cylinders may be separated to give space for the grippers, when the same are passing between the cylinders. The cylinders are separated from each other at 20 the time the advance end of the bag section is advanced into position to be engaged by the grippers, and the latter are actuated to grasp the same. After the grippers have been operated to grip the bag section, and 25 before the grippers are actuated to release the same, the lower cylinder rises so that the bag section is gripped between the cylinders and fed forward by the same. The grippers 115, 115 which engage the margins of the 30 upper and lower folds of the bellows folds, are automatically actuated to grasp the same, at the proper time, at the ends of the transverse folding line which has been determined by the creasers. The infolded 35 part of the bellows folds are forced outwardly by the spreaders just before the grippers release their hold, so that the sides of the bottom of the bag will be drawn straight by the action of the grippers and 40 side clamps, thereby insuring the accurate formation of the upright side folds at the bottom of the bag, as clearly indicated by the dotted lines in Fig. 8. As the bottom 45 of the bag is carried downwardly between the cylinder 86 and feed roller 95, the upper flap of the bottom, previously held by the grippers against the cylinder 102, will be folded back on the body of the bag section, as heretofore done in the operation of making paper bags.

I claim as my invention:—

1. In a paper bag machine, the combination with a tongue plate adapted to support a bellows folded tube, of two sets of rotative 55 knives located one above and one below said tongue plate, each set consisting of a transverse knife and two longitudinally arranged knives adapted to make a central transverse cut and two longitudinal cuts in the top and 60 bottom folds of the tube, a pair of feed rollers located one above and the other below said tongue plate, provided with two laterally separated transverse knives adapted to make transverse cuts extending through the 65 side margins of the tube, and a second pair

of feed rollers located one above and the other below said tongue plate, and provided with laterally separated transverse knives located in position to make transverse cuts connecting said marginal cuts with the central transverse cuts. 70

2. In a paper bag machine, the combination with a tongue plate adapted to support a bellows folded tube, of two sets of rotative knives, each set consisting of a transverse 75 knife and two longitudinally arranged knives, a pair of feed rollers provided with two laterally separated transverse knives and with two laterally separated transverse creasers, adapted to cut and crease the marginal parts of the tube, and a second pair of feed rollers provided with two laterally separated transverse knives and with two laterally separated, transverse creasers, adapted to cut and crease the tube inside of 80 85 the side margins thereof.

3. In a paper bag machine, the combination with upper and lower tongue plates adapted to receive a bellows folded tube, of 90 rotative shafts located above and below said tongue plates, knife bars mounted transversely on said shafts and having endwise sliding movement thereon, each knife bar carrying a transverse knife, two longitudinal knives mounted on each shaft, one at each 95 side of the transverse knife thereon, and means giving endwise movement to said knife bars to advance the knives thereon toward the tongue plates, said tongue plates being provided with knife receiving apertures. 100

4. In a paper bag machine, the combination of a tongue plate adapted to support a bellows folded tube, two sets of knives operating to make central transverse cuts and 105 two longitudinal cuts in the top and bottom layers of said tube, a pair of feed cylinders each provided with a central shallow groove and one of which has two transverse knives adapted to make transverse cuts through 110 the side margins of the bellows folded tube, and a second pair of feed cylinders provided each with a central shallow groove and two lateral grooves and one of which has two transverse knives adapted to sever the 115 bellows folded tube transversely between its center and side margins, said tongue plate extending between both of said pairs of feed cylinders, and said tongue plate being provided adjacent to the first named pair of 120 feed cylinders with opposite lateral notches forming a central longitudinal part which passes through the grooves of said first named pair of feed cylinders, and being also provided, adjacent to the second named pair of feed cylinders, with two oppositely arranged apertures forming central and lateral longitudinal parts which extend through the central and lateral grooves of said second named pair of feed cylinders. 125 130

5. In a paper bag machine, the combination with a tongue plate adapted to support a bellows folded paper tube, of two rotative feeding and gripping cylinders provided 5 with gripping means and arranged one above the other, the lower one of said cylinders having shifting movement toward and from the upper cylinder, and means for giving shifting movement to the lower cylinder adapted to separate the cylinders at the 10 time the severed bag section is advanced to and gripped by the grippers on said cylinders; said tongue plate being provided with oblique spring fingers adapted to partly 15 open the forward end of the bag section as the same enters between said cylinders.

6. In a paper bag machine, the combination of a tongue plate, a pair of shafts provided with transverse and longitudinal cutters adapted to form central transverse cuts 20 and two longitudinal cuts in the upper and lower layers of a bellows folded tube, a pair of feed cylinders, each provided with a central groove one of which has two transverse 25 cutting knives adapted to make transverse cuts through the side margins of the tube, a second pair of feed cylinders each provided with a central and two lateral grooves, and one of which has two cutting knives 30 adapted to completely sever a bag section from the tube, a pair of feeding and gripping cylinders, one of which has shifting movement toward and from the other and both of which are provided with gripping 35 means, means for giving shifting movement to the movable feeding and gripping cylinders, said tongue plate extending between said pairs of feed cylinders and being provided with opposite lateral notches forming a central longitudinal part which extends through 40 the central grooves in the first named pair of feed cylinders, and also, adjacent to the second named pair of feed rolls, with two laterally opposite apertures forming a central and two lateral, longitudinal parts 45 which extend through the central and lateral grooves in the second named pair of feed cylinders, said tongue plate having at its end adjacent to the said feeding and gripping cylinders oblique spring fingers which 50 operate to spread the forward end of the bag section as it enters between said cylinders and is engaged by the grippers thereon.

7. In a paper bag machine, the combination of knives adapted to form tongues on the top and bottom layers of a bag section and to completely sever a bag section from a bellows folded tube, of means for forming a diamond fold on the bag section comprising two feeding and gripping cylinders, each provided with four grippers, two of which are located in position to grip the side edges of one of the tongues on the end of the bag section and the other two of which are 60 located in position to grip the side margins

of one of the bellows folds, and means for actuating the said grippers, one of said cylinders being movable toward and from the other one, and means for giving shifting movement to the movable cylinder. 70

8. In a paper bag machine, the combination with a tongue plate adapted to support a bellows folded paper tube, of knives adapted to form tongues on the top and bottom layers of a bag section and to completely sever said bag section from the tube, a pair of feeding and gripping cylinders, each provided with four grippers, two of which are located in position to grip the side edges of one of the tongues on the bag section and two of which are located in position to grip the side margins of one of the bellows folds, one of said feeding and gripping cylinders being movable toward and from the other one, means for giving shifting movement to the movable cylinder, and means for actuating said grippers, said tongue plate having at its end adjacent to said feeding and gripping cylinders oblique spring fingers which operate to spread the forward end of the bag section as it enters between said cylinders and is engaged by the grippers thereon. 80

9. In a paper bag machine, the combination with a rotative cylinder, of gripping means thereon embracing a fixed gripper jaw on the cylinder, a gripper arm extending transversely of the cylinder and provided at its end, at one side of the cylinder, with a gripping finger, an operating lever pivoted to the cylinder and arranged longitudinally thereof, with one of its ends projecting beyond the end of the cylinder, said operating lever being connected with and giving endwise movement to said gripper arm, an obliquely arranged link connecting the said gripper arm at a point between its ends with the cylinder, and means acting on the projecting end of the said operating lever for actuating the same. 90

10. In a paper bag machine, the combination with a rotative cylinder, of gripping means thereon embracing a fixed gripper jaw on the cylinder, a gripper arm extending transversely of the cylinder and provided at its end, at one side of the cylinder, with a gripping finger, a member arranged longitudinally of the cylinder and adapted to move laterally thereof, to which the main end of said gripper arm is pivoted, an obliquely arranged link connecting the said gripper arm at a point between its ends with the cylinder, an operating lever pivoted to the cylinder and extending longitudinally thereof to a point beyond the end of the cylinder, a link connecting said operating lever with the said member to which the gripper arm is pivoted, and means acting on the projecting end of said operating lever for actuating the same. 100

11. In a paper bag machine, the combination with a hollow rotative cylinder, provided with a longitudinal recess at one side thereof and with an aperture in the side thereof diametrically opposite said recess, of gripping means embracing a longitudinally arranged supporting bar secured in said recess, a bracket attached to said bar and extending transversely of the cylinder with its outer end seated in said aperture, a gripper arm movably connected with said bracket and provided with a gripper finger which co-acts with the end of said bracket, said gripper arm having endwise movement in a direction transversely of the cylinder and its finger-bearing end having swinging movement in a direction endwise of the cylinder, and actuating means for the said gripper arm embracing a longitudinally arranged operating lever pivoted to said supporting bar and extending beyond the end of the same, and means acting on the projecting end of said operating lever for actuating the same.
12. In a paper bag machine, the combination with a hollow rotative cylinder provided with a longitudinal recess at one side thereof and with an aperture in the side thereof diametrically opposite said recess, of gripping means embracing a longitudinally arranged supporting bar secured in said recess, a bracket attached to said supporting bar and extending transversely of the cylinder with its outer end seated in said aperture, a gripper arm arranged transversely of the cylinder and provided with a gripper finger which co-acts with the outer end of said bracket, an obliquely arranged link connecting said gripper arm with said bracket, a member to which the inner end of said gripper arm is pivotally connected and which has movement in a direction laterally of the cylinder, a longitudinally arranged operating lever pivoted to the said supporting bar and extending beyond the end of same, said operating lever being connected with said member to which the inner end of the gripper arm is pivoted, and means acting on the projecting end of said operating lever for actuating the same.
13. In a paper bag machine, the combination with a hollow rotative cylinder provided with a longitudinal recess at one side thereof and with apertures near the ends of the cylinder in the side thereof diametrically opposite said recess, and gripping means embracing a longitudinally arranged supporting bar secured in said recess, a bracket attached to said bar and provided with two arms that extend transversely of the cylinder with their outer ends seated in said apertures, gripper arms arranged longitudinally of said bracket arms and provided with gripper fingers which co-act with the ends of said bracket arms, obliquely arranged links con-
- necting said gripper arms with said bracket arms, longitudinally arranged levers pivotally connected at their inner ends to said bracket and at their outer ends to said gripper arms, two operating levers pivoted to said supporting bar and extending at their outer ends beyond the ends thereof, the inner ends of said operating levers being connected with said levers to which the gripper arms are pivoted, and means acting on the projecting ends of said operating levers for actuating the same.
14. In a paper bag machine, the combination with a hollow rotative cylinder provided with a longitudinal recess at one side thereof, and with a central longitudinal slot in the side thereof diametrically opposite said recess, of gripping means embracing a longitudinally arranged supporting bar secured in said recess, a bracket attached centrally to said supporting bar and extending transversely of the cylinder with its outer ends seated in said slot, gripper arms arranged longitudinally of said bracket and provided with gripper fingers which co-act with the end faces of the bracket, obliquely arranged links connecting said gripper arms with said bracket, a transversely arranged, longitudinally movable slide bar mounted on said bracket, a longitudinally arranged bar attached to said slide bar and to which said gripper arms are pivoted at their inner ends, a longitudinally arranged operating lever pivoted to said supporting bar and connecting at its inner end with said slide bar, said operating lever extending at its outer end beyond the end of said bar, and means acting on the projecting end of said operating lever for actuating the same.
15. In a paper bag machine, the combination with two co-acting cylinders provided with gripping means and one of which is movable toward and from the other, means for shifting the movable cylinder toward and from the stationary one at each rotation of the cylinders, and means for driving one of said cylinders from the other cylinder maintaining constant driving connection between said cylinders.
16. In a paper bag machine, the combination with two co-acting cylinders provided with gripping means, one of said cylinders being movable toward and from the other, sliding journal boxes supporting the movable cylinder, and means for shifting the movable cylinder toward and from the stationary one, comprising horizontally arranged, pivoted levers which are connected with and give movement to said journal boxes, and two rotative cams severally acting on the said levers.
17. In a paper bag machine, the combination with two cylinders provided with gripping means, shafts on which said cylinders are mounted and journal boxes for said

shafts, the journal boxes for the shaft of one of the cylinders having sliding movement on the machine frame, affording shifting movement of one of said cylinders toward 5 and from the other, and driving means for actuating one of said cylinders from the other one comprising beveled gear wheels attached to said shafts outside of the journal boxes, two beveled gear wheels mounted 10 upon said journal boxes and intersecting with those on the shafts, and a shaft for transmitting motion from one to the other of said beveled gear wheels on the journal boxes, having endwise sliding and splined 15 connection with one of the same.

18. In a paper bag machine, the combination with two co-acting cylinders provided with gripping means, one of said cylinders being movable toward and from the other, 20 means for giving shifting movement to said movable cylinder toward and from the other cylinder during each rotation of the cylinders, movably mounted journal boxes for the movable cylinder having shifting movement 25 on the machine frame, a feed cylinder co-acting with one of said gripper cylinders, a shaft on which said feed cylinders are mounted, and journal boxes for said feed cylinder shaft, mounted on the said shifting 30 journal boxes of the movable gripper cylinder.

19. In a paper bag machine, the combination with two co-acting cylinders provided with gripping means, one of said cylinders being movable toward and from the other, 35 journal boxes for the movable cylinder having shifting movement on the machine frame, a feed cylinder co-acting with the movable gripper cylinder, a shaft on which 40 said feed cylinder is mounted, journal boxes for said feed cylinder shaft, mounted on the shifting journal boxes of the movable gripper cylinder, and intermeshing gear wheels on the shafts of said movable gripper 45 cylinder and feed cylinder, for driving said feed cylinders from the said movable gripper cylinder.

20. In a paper bag machine, the combination with two co-acting cylinders provided with gripping means, of two spreader arms, 50 rock-shafts arranged parallel with each other and transversely to the said cylinders, to which said spreader arms are rigidly attached, rocker lugs attached to said rock-shafts and extending toward each other, a 55 rocker arm adapted to bear upon and actuate both of said rocker lugs, and means for actuating said rocker arm.

21. In a paper bag machine, the combination with two cylinders located one above 60 the other and provided with gripping means, of two spreader arms located at the delivery side of said cylinders, parallel horizontal rock-shafts arranged transversely of the cylinders above the upper cylinder, to 65 which rock-shafts said spreaders are rigidly attached, rocker lugs attached to said rock-shafts and extending toward each other, a rock-shaft arranged above and parallel with 70 said cylinders and provided with a rocker-arm adapted to act upon said rocker lugs, said rock-shaft being provided with a rigidly attached crank-arm, an upright operating lever, a connecting rod pivoted to said crank-arm and to said operating lever, and a 75 rotative cam acting on said lever for giving movement to said spreaders.

22. In a paper bag machine, the combination with two co-acting rotative cylinders located one above the other and provided 80 with gripping means, of two vertically arranged ironers, located at the delivery side of said cylinders, and means for supporting and operating said ironers comprising two parallel rock shafts, located one above the 85 other, parallel crank arms on said rock-shafts, engaged with and supporting said ironers, and means for giving movement to said rock-shafts.
